UNITED STATES PATENT OFFICE

167,346

PLANTER

William W. Goodman, Los Angeles, Calif.

Application April 28, 1952, Serial No. 19,505

Term of patent 14 years

(Cl. D35—3)

To all whom it may concern:

Be it known that I, William W. Goodman, a citizen of the United States, residing at Los Angeles, in the county of Los Angeles and State of California, have invented a new, original, and ornamental Design for Planter, of which the following is a specification, reference being had to the accompanying drawing, forming a part hereof, in which:

Fig. 1 is a front elevational view of a planter, showing my new design.

Fig. 2 is a side elevational view of the planter shown in Fig. 1.

I claim:

The ornamental design for a planter, as shown.
WILLIAM W. GOODMAN.
